Primary Examiner — Richard Kearney*Assistant Examiner* — Qiawen W Wiechert(74) Attorney, Agent, or Firm — Mehdi (Afshin) Zamanpour(57) CLAIM

The ornamental design for a cabinet, as shown and described.

DESCRIPTION

FIG. 1 is a top perspective view of a cabinet, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a top perspective view showing the cabinet in a close state thereof.

The dash-dash broken lines in the drawings illustrate the portions of the cabinet, which form no part of the claimed design.

1 Claim, 9 Drawing Sheets(56)
